UNITED STATES PATENT OFFICE

NATHANIEL B. UPDIKE, OF LONEGUM, VIRGINIA.

DESIGN FOR A GARMENT-HOOK.

SPECIFICATION forming part of Design No. 31,177, dated July 11, 1899.

Application filed June 17, 1899. Serial No. 721,006. Term of patent 7 years.

To all whom it may concern:

Be it known that I, NATHANIEL B. UPDIKE, a citizen of the United States, residing at Lonegum, in the county of Bedford and State of Virginia, have invented and produced a certain new and original Design for Garment-Hooks; and I do declare the following to be a full, clear, and exact description of the invention, such as will enable others skilled in the art to which it appertains to make and use the same.

The invention relates to a new and original design for garment-hooks.

The object of the invention is to provide a device of this character to support garments and which is provided with means for holding an explosive—such, for instance, as a fire-cracker—whereby should the walls of the room catch fire the ascending flames will ignite the fuse of the fire-cracker and the explosion of the cracker will notify the occupants of the house of the condition of affairs.

In the drawings, Figure 1 is a perspective

view, and Fig. 2 is a longitudinal sectional view.

25

The leading feature of my design consists of the base 1, having holes 2, the upwardly-projecting hook 3, and the longitudinal bore or pocket 4.

A fire-cracker is adapted to be inserted in 30 the pocket, which will, when exploded by the ascending flames, notify the occupants of the building.

What I claim is—

The design for a garment-hook, as herein 35 shown and described.

In testimony whereof I have hereunto set my hand in presence of the subscribing witnesses.

NATHANIEL B. UPDIKE.
